CLAIM

The ornamental design for a bowl, as shown and described.

DESCRIPTION

FIG. 1 is a top isometric view of a bowl showing a first embodiment of the design;

FIG. 2 is a bottom isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and

FIG. 8 is a bottom plan view thereof.

FIG. 9 is a top isometric view of a bowl showing a second embodiment of the design;

FIG. 10 is a bottom isometric view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The shading lines shown in the drawings represent the three-dimensional contour of the claimed design and are not intended to indicate surface decoration. The dashed lines shown in the drawings illustrate portions of the bowl that form no part of the claimed design.
